(57) **CLAIM**

(21) Appl. No.: **29/124,650**

The ornamental design for a satellite speaker for a multi-media computer speaker system, as shown and described.

(22) Filed: **Jun. 8, 2000**

DESCRIPTION

Related U.S. Application Data

(63) Continuation of application No. 29/113,963, filed on Nov. 15, 1999, now abandoned.

FIG. 1 is a right side elevational view of a satellite speaker for a multimedia computer speaker system showing our new design;

(51) **LOC (7) Cl. 14-01**

FIG. 2 is left side elevational view thereof;

(52) **U.S. Cl. D14/214**

FIG. 3 is a rear elevational view thereof;

(58) **Field of Search** D14/204, 207, D14/209-216; 181/144-148, 153, 157, 198-199; 381/300-302, 307, 359, 361, 363, 386

FIG. 4 is a front elevational view thereof;

(56) **References Cited**

FIG. 5 is a top plan view thereof; and,

U.S. PATENT DOCUMENTS

FIG. 6 is a bottom plan view thereof.

D. 318,054 * 7/1991 Kikutani D14/214

The broken line showing on FIGS. 1-6 is for illustrative purposes only and forms no part of the claimed design.
